(57) **CLAIM**

Claim the ornamental design for a portico shade system operable with a tent, as shown and described.

DESCRIPTION

FIG. 1 illustrates a perspective view of a portico shade system operable with an exemplary tent, wherein the portico shade system is formed in accordance with one exemplary embodiment of the present invention, and wherein the portico shade system is positioned in one exemplary configuration;

FIG. 2 illustrates a front view of the portico shade system of FIG. 1;

FIG. 3 illustrates a side view of the portico shade system of FIG. 1;

FIG. 4 illustrates a perspective rear view of the portico shade system of FIG. 1; and,

FIG. 5 illustrates a perspective view of a portico shade system operable with an exemplary tent, wherein the portico shade system is formed in accordance with another exemplary embodiment of the present invention, and wherein the portico shade system is positioned in an exemplary configuration.

The broken lines shown in FIGS. 1-5 are for illustrative purposes only and form no part of the claimed design.
